UNITED STATES PATENT OFFICE.

MARIANO ROSALES, OF SAN ANTONIO, TEXAS.

FLOAT-OPERATED CIRCUIT CLOSER.

Application filed June 22, 1925. Serial No. 38,617.

This invention relates to improvements in indicators, particularly oil indicators for automobiles or the like and it is the principal object to provide an electrical oil indicator which is float controlled.

Another object of the invention is the provision of an electrical oil indicator in which a float operates to close an alarm circuit to indicate that the supply of oil must be replenished.

A further object of the invention is the provision of an electrical oil indicator of simple and inexpensive construction, yet effectively operating to positively indicate the need of supplying oil to the parts to be lubricated or to replenish the oil supply for instance in the engine crank case.

These and other objects and advantages of the invention will become more fully apparent as the description thereof proceeds, and will then be specifically defined in the appended claims.

In the accompanying drawing, forming a material part of this disclosure:

25 Fig. 1 is a perspective view of an apparatus or electrical oil indicator constructed according to the present invention.

Fig. 2 is a longitudinal section through the same.

30 Fig. 3 is a top plan view of the apparatus.

Fig. 4 is a section on line 4—4 of Figure 3.

Fig. 5 is a longitudinal section on line 5—5 of Figure 2.

35 Fig. 6 is a bottom plan view of the top part of the apparatus seen in the direction of the arrows 6—6, Figure 5.

Fig. 7 is a top plan view seen in the direction of the arrows 7—7, Figure 5.

Fig. 8 is a diagrammatical view showing 40 the electrical connections.

The apparatus comprises a casing or housing 10 having a lateral extension 11, both closed at the top by means of a plate 12 having an opening 13 therein. At the bottom or near to the same, the oil inlet 14 is provided adapted to be closed by a screw plug or the like.

45 A plurality of vertically disposed rods 15 are interposed between bottom and top of the casing and act as guides for the float 16 to the top part of which a socket 17 is attached adapted to receive and hold the lower end of a float operated bar 18 consisting of two parts connected intermediate 50 their ends by a joint 19 allowing a bending of the bar at this point in the manner of

a knee. Near its upper end a similar joint 20 allows the attachment of an operating rod 21 to bar 18 adapted to pass through the opening 13 into a casing 22 secured to the top of casing 10 having an air vent 23 in one of its side walls.

The top plate 24 of casing 22 is made of fibrous material, and carries four contact screws or binding posts 25, 26, 27 and 28, two of which are connected by means of the wires 29, 30 to contacts 36 and 37 supported by a fibre block 35 slidable between rails 31, 32, and adjustable therealong by means of adjusting screw bolts 33 and 34. 70 A contact 38 is connected to a spring 38' having electrical connections with contact 36, and another contact 39 is engageable with contact 38, said contact 39 being electrically connected with contact 37. The 75 other two of the contacts 27, 28 are connected by wires to contacts 36' and 37' supported by a fibre block 35' slidable between rails 31, 32, and adjustable therealong by means of adjusting screw bolts 47 and 48. 80 A contact 45 is connected to a spring 44 having electrical connections with contact 37, and another contact 45' is engageable with contact 45, said contact 45' being electrically connected with contact 36'. Binding post 25 is grounded, shown in Fig. 8, while post 26 is in circuit with a bell 40, battery 40^b, and ground 41. Posts 27 and 28 are in circuit with the electrical sparking system of the automobile, connected 90 thereto by wires 42 and 43.

The operation of the device will be evident from the above description without further detailed explanation.

If the supply of oil within the container 95 10 has fallen below a predetermined level, determined by the respective adjustment of the screws 33, 34, the float actuated rod 21 will close the bell circuit by abutting against spring 38', and the bell will give an acoustic alarm signal. If the oil supply is not replenished, the rod 21 will continue to move as the float descends due to the diminishing supply of oil, and will finally also reach spring 44, abutting thereagainst, thereupon 100 opening the contacts 45, 45', and breaking the ignition circuit, causing the engine to stop. The position of spring 44 is adjusted by the screws 47, 48.

105 While I have shown and described the preferred form of my apparatus as an example of the many ways of practically con-

structing the same, it is to be understood, that such changes may be made in the general arrangement and in the construction of the minor details thereof, as fall within 5 the scope of the appended claims, without departure from the principle involved.

Having thus described my invention, what I claim as new and desire to secure by Letters Patent is:

- 10 1. In a device of the class described, having a pivoted rod movable by a float, the combination of a casing, rails depending from said casing, blocks slideable between said rails, adjusting screws engaging said casing, and abutting said blocks, springs depending from said blocks and projecting into the line of movement of said rod, contacts on said springs, other contacts engageable with said contacts, and depending from 15 said blocks, some of the latter contacts being located in the front of said springs, and other of the latter contacts being located in the rear of said springs, whereby a forward movement of said rod closes a pair of said 20

coactive contacts, and a continued forward 25 movement opens another pair of said coactive contacts.

2. In a device of the class described, an oil operated float switch, comprising a float, lever arms connected to said float, a pivoted 30 rod moved by said lever arms, a casing into which said pivoted rod projects, rails depending from said casing, blocks slideable between said rails, adjusting screws engaging said casing, and abutting said blocks, 35 springs depending from said blocks and projecting into the line of movement of said rod, contacts on said springs, other contacts engageable with said contacts, and depending from said blocks, whereby a forward 40 movement of said rod closes a pair of said coactive contacts, and a continued forward movement opens another pair of said coactive contacts.

In testimony whereof I have affixed my 45 signature.

MARIANO ROSALES.
